UNITED STATES PATENT OFFICE

2,571,272

NECK RESIZER AND BULLET SEATER

George J. Martin, Detroit, Mich.

Application July 31, 1948, Serial No. 41,807

3 Claims. (Cl. 86—24)

1

My invention relates to a new and useful improvement in a neck resizer and bullet seater adapted for use in resizing and centering the neck of a shell prior to the forcing of a bullet therein, the invention being adapted primarily for use in loading shells which have been previously used and particularly that type of shell used in a rifle which has the forward end of it reduced in size compared to the powder containing portion.

Experience has shown that the reduced neck portion of the shell loses its proper size upon being used and also the reduced neck forming portion becomes distorted out of center relatively to the remaining portion of the shell. The consequence is that when a bullet is placed in the open end of the neck forming portion this bullet is not properly gripped by the neck forming portion and is not properly centered relatively to the shell so that it is not properly centered relatively to the rifle bore resulting in an imperfect travel of the bullet after being projected from the muzzle of the rifle.

It is an object of the present invention to provide a device whereby the neck may be re-sized and properly centered relatively to the shell and the bullet centered while being forced within the neck forming portion so as to retain these parts in proper size and proper centering.

It is another object of the present invention to provide a structure whereby this operation may be performed and whereby the depth of thrust of the butt end of the bullet into the open end of the neck forming portion of the shell may be adjusted and regulated.

Another object of the invention is the provision of a mechanism for performing the operation referred to and which will be simple in structure, economical to manufacture, durable, compact, and highly efficient in use.

Another object of the invention is the provision of a device of this class of a bushing for reception of the large portion of the shell so as to snugly receive it and a bushing centered relatively to the first named bushing and having a bore formed therein for the projection of the neck forming portion of the shell thereinto which bore is of proper size so as to properly size the neck which is centered to the first named bushing.

Other objects will appear hereinafter.

It is recognized that various modifications and changes may be made in the detail of structure illustrated without departing from the invention and it is intended that such will be embraced within the scope of the claims which form a part hereof.

2

Forming a part of this specification are drawings in which,

Fig. 1 is a central, longitudinal, sectional view of the invention,

5 Fig. 2 is a sectional view taken on line 2—2 of Fig. 1,

Fig. 3 is a sectional view taken on line 3—3 of Fig. 1.

As shown in the drawings the invention comprises a structure which is adapted for being supported on a suitable support and to illustrate the use of the invention I have indicated a support embodying the telescopic standards 14 and 15 on which is mounted a bracket 16 which may be 10 clamped on the standard 15 in its various positions by means of the hand wheel 17 which serves to tighten or loosen a screw. Rotatably mounted in the bracket 16 is a gear 18 which may be rotated by the shaft 19 bearing the hand rod 20. 15 This gear is adapted to mesh with rack teeth 21 on the rod 22 which carries a head or plate 23.

20 The invention comprises a tube 9 having the threaded portion 10 at one end on which is threaded an adjusting nut 11 which engages in a 25 slot 12 formed in the supporting head 13. The construction is such that by rotating the nut 11 the tube 9 may be moved upwardly or downwardly relatively to the head 13.

25 Slidably mounted in the tube 9 and centered 30 relatively thereto is a bushing 24 which has a bore 27 of an inside diameter exactly corresponding to the outside diameter of the base portion of the shell provided at its butt end with the rim or flange 26 adapted to engage the bed or plate 23. 35 This bushing is formed of hardened metal and is machined to close dimensions both on its periphery and in its bore 27 and the bore of the tube 9 is machined to close dimensions so that the bore 27 is properly and exactly centered relatively to 40 the tube 9.

45 Fixedly mounted in the upper end of the tube 9 by a press fit is a bushing 28. The periphery of this bushing 28 is machined to close dimensions so as to fit perfectly in the bore of the tube 9 in a press fit. This bushing 28 is provided with an internal bore 29 which is also finished to fine dimensions and properly centered relatively to the bushing 24. Embracing the portion of the bushing 28 is a coil spring 31

50 which is adapted to engage one end of the bushing 24 and normally tends to move the same downwardly of the bushing 9, this downward movement being within the limits of the peripheral slot 38 formed in a bushing 24 and in which 55 engages a screw 39 threaded inwardly from the

periphery of the tube 9. The bore 29 of the bushing 28 is sized to the proper size of the reduced or neck forming portion 30 of the shell which it is intended to operate upon. Consequently when the shell is thrust inwardly of the bore 29 while the larger portion of the shell 25 is retained in the bushing 24 the neck forming portion 30 will be properly sized and also brought into center relatively to the remaining portion of the shell.

The tube 9 is provided at its upper end with the internally threaded portion 33 in which is threaded a screw 35 having the outwardly projecting end 34 whereby the screw may be rotated. The inner end 36 of this screw is reduced in diameter so as to exactly fit the bore 29 of the bushing 28 and formed in the end of this portion 36 is a socket which is formed to conform to the curvature of the bullet 40. This socket 37 is centered relatively to the bore of the bushings 24 and 28 so that, as the point of the bullet 40 enters the socket 37 it will be centered.

In operation, the shell 25 would be filled with the proper charge of powder and the bullet 40 thrust slightly into the open end of the neck forming portion 30 whereupon the shell would then be placed within the bushing 24, with the butt end projecting slightly outwardly therefrom. The presser member 23 would then be moved upwardly to press the shell firmly into the bushing 24 and at the same time force the bushing 24 upwardly into the position shown in Fig. 1. In this upward movement the neck forming portion 30 would enter the bushing 28 and the neck would then be properly sized. As the neck proceeds upwardly in the bore of the bushing 28 the bullet end would contact the socket 37 and further upward movement would force the bullet into the neck forming portion the desired distance. This distance may of course be varied by moving the part 36 upwardly or downwardly so that the depth of the insert of the bullet 40 may be thus regulated and adjusted.

Experience has shown that when a shell is operated upon in this manner the bullet will be properly seated and properly centered relatively to the shell and the neck will be sized, all of this requiring the single operation as described.

What I claim as new is:

1. A shell neck resizer and bullet seater of the class described comprising a supporting tube having a bore formed therethrough; a bushing slidably mounted in said bore and having its bore centered relatively to the axis of the bore of said tube and adapted for reception of a shell at the large portion thereof; a sizing bushing mounted in said tube in spaced relation to said first named bushing and having a bore formed therethrough centered relatively to the axis of said slidable bushing and of a size for the reception of a reduced neck forming portion on said shell upon movement of said slidable bushing into approach to said sizing bushing, said slidabie bushing having a longitudinal groove formed in its periphery and said tube having a stud pro-

jecting inwardly and engaging in said groove for limiting longitudinal movement of said slidabie bushing.

2. A shell neck resizer and bullet seater of the class described comprising a supporting tube having a bore formed therethrough; a bushing slidably mounted in said bore and having its bore centered relatively to the axis of the bore of said tube and adapted for reception of a shell at the large portion thereof; a sizing bushing mounted in said tube in spaced relation to said first named bushing and having a bore formed therethrough centered relatively to the axis of said slidabie bushing and of a size for the reception of a reduced neck forming portion on said shell upon movement of said slidabie bushing into approach to said sizing bushing; and a socket bearing body projecting inwardly of said tube and having a socket formed on its inner end for engagement with the end of a bullet, said socket being centered relatively to the bores of said bushings for centering said bullet relatively to the bores of said bushings and forcing said bullet into the reduced neck forming portion of the shell upon movement of said slidabie bushing into approach to said sizing bushing a predetermined distance.

3. A shell neck resizer and bullet seater of the class described comprising a supporting tube having a bore formed therethrough; a bushing slidably mounted in said bore and having its bore centered relatively to the axis of the bore of said tube and adapted for reception of a shell at the large portion thereof; a sizing bushing mounted in said tube in spaced relation to said first named bushing and having a bore formed therethrough centered relatively to the axis of said slidabie bushing and of a size for the reception of a reduced neck-forming portion on said shell upon movement of said slidabie bushing into approach to said sizing bushing, and a socket bearing body projecting inwardly of said sizing bushing from one end thereof and having a socket formed at its inner end for engagement with the end of a bullet; said socket being centered relatively to the bores of said bushings for centering said bullet relatively to the bores of said bushings and forcing said bullet into the reduced neck-forming portion of the shell upon movement of said slidabie bushing into approach to said sizing bushing a predetermined distance, the inner end of said sizing bushing projecting beyond the inner end of said socket bearing body.
